PACKING FOR FRAGILE ARTICLES

Leon Mann, Mount Vernon, N. Y., assignor to
Holed-Tite Packing Corporation, New York,
N. Y., a corporation of New York

Application March 12, 1930, Serial No. 435,094

6 Claims. (Cl. 217—21)

The present improvements relate, in general to packing for fragile articles and more particularly, to an improved holder for articles such as bottles and the like.

5 A primary object, among others, of the improvements, is to provide an article holder in the form of a tray which is automatically adjustable to accommodate articles of varied sizes. A further object is to provide an improved tray 10 which is resilient and which will exert a gripping action on the packed articles, tending to hold them in place and against wobbling.

Another object is to provide a filler for an outer carton, wherein said filler is oversize for being 15 compressed within the carton. A still further object is to provide an improved packing for bottles wherein the receiving portions are oversize for accomplishing a plurality of purposes.

To provide an improved cushioning means for 20 bottles constitutes a further object of the improvements. Other objects and advantages of the improvements will be apparent upon reference to the accompanying specification and drawings in which—

25 Fig. 1 is a perspective of a carton with one form of the improvements disposed therein;

Fig. 2 is a section of the improved filler-tray;

Fig. 3 is a section on line 3—3 of Fig. 1;

Fig. 4 is a bottom plan view of a portion of 30 one embodiment of the improvements;

Fig. 5 is an enlarged diagrammatic view of a portion of the tray;

Fig. 6 is a section of an actual size recess of the tray, having a full size ginger ale bottle 35 therein;

Fig. 7 is a section of a modified form;

Fig. 8 is a section on line 8—8 of Fig. 7;

Figs. 9 and 10 are sections of other modified forms.

40 Although the embodiments of the present improvements may be manufactured in any desired manner, they are preferably made of resilient material, such as pulp fibres, by the pulp sucking or felting process. In this manner the entire holder or filler, as well as all parts thereof, are created complete in one operation. Accordingly, the holder and preformed parts thereof are relatively rigid, but possesses inherent resiliency and elasticity so as to be readily expandible and compressible. These qualities not only contribute a cushioning effect but also, in the present improvements, provide adjustability as will hereinafter appear.

The present invention is in the nature of an 55 improvement on the construction described and

claimed in my prior Patent #1,809,559, filed December 14, 1927 and granted June 9, 1931.

Referring to the drawings, the embodiment chosen for illustration comprises a tray 15 having a series of bottle-shaped depressions or recesses 16, which are adapted to receive bottles in reclining position. Said recesses or pockets are preformed with the tray, at the time of manufacture, and have alternate neck and body portions for conforming to the contour of such 65 articles. While this form of the invention is particularly adapted for packing bottles, it is obvious that other types of article-conforming recesses may be provided to suit the nature and shape of the merchandise.

Referring more particularly to the recesses 16, it is notable that they are deeper than a half bottle section. In Figs. 3, 5 and 6, the horizontal dotted line represents the horizontal medial line of the bottles when they rest in the recesses or 75 pockets. It is therefore seen that the upper wall portions, defining the recess mouth, extend above the medial line of the bottle. Likewise, upon inspection of Fig. 6, it is apparent that the recess is normally larger or wider at the upper or mouth 80 portion, than the bottle diameter. In this figure, the portion of the tray is illustrated in its normal state, i. e., before insertion in a surrounding carton, while the bottle B resting therein is actual size.

The pockets or recesses 16 also extend substantially the width of the tray and are somewhat longer than the bottles to be packed. This provision permits the bottles to be staggered or slightly offset with respect to one another (Fig. 90 1) so that their shoulders are slightly spaced, well cushioned and protected by the shoulder portions 17 of the recesses.

Due to the taper of the bottle from its body portion, through the shoulder portion to the neck 95 portion where its diameter is materially less, it is evident that the shoulder and neck portions of the pocket or recess will be deeper than the corresponding half sections of the bottle at these points. In fact, since the bottle tapers away, but the ridges 18 are in the same horizontal plane from tray edge to tray edge, the shoulder and neck portions of the recesses are almost equal to the diameters of these portions of the bottle, and in some instances the neck portions of 100 the recesses will be deeper than the diameter of the bottle neck. Furthermore, the curvature of the shoulder portion 17 of the recess from the body to the neck is gradual, and is less sharp than the curvature of the bottle shoulder, so that slight 105 110

movement of the recess walls at this point for approaching the bottle shoulder is permitted. The recesses 16 may be closed at one or both ends 19 and 20, which not only retain the bottles in position, but also serve as cushions or buffers for protecting the bottles from end pressures and shocks. The ends of the tray may be provided with cushion flaps 21 having integral protuberances 22 for cushioning the tray at these points.

10 Closed ends 20 may be omitted, if desired.

Upon reference to Figs. 1 to 3, the greater size of the tray 15 in comparison to the carton 25 is illustrated. This oversize of the tray is only of the dimension laterally of the recesses or 15 substantially at right angles to their longitudinal extent. Accordingly, the tray must be contracted or compressed in order to insert it in the carton 25 of smaller dimension. Such contraction of the tray, automatically causes the elements thereof to shift position. This necessary 20 adjustment of the tray so that it can be disposed in the smaller dimension carton, obviously compels a slight lateral transposition of the recesses. In Fig. 5, the full and dotted lines diagrammatically illustrate this shifting of the 25 position of the recesses as well as the altered shape thereof attending the compression of the tray. The relative sizes of the tray 15 and carton 25 may be varied, depending on the degree 30 of adjustability and size of pockets desired.

As seen in dotted lines in Fig. 5 and also in Fig. 3, the attenuation of the tray causes adjacent pocket walls to approach one another, thereby more nearly defining a half bottle shape 35 while the upper walls of the pockets are closer and may curve or extend inwardly a slight degree at and above the horizontal medial line of the bottles to be received. Portions of the mouths of the recesses, when the tray is in the 40 carton (Fig. 3), therefore are slightly less than the diameter of the bottles. Accordingly, when inserting the bottles, these mouth portions yield to permit reception of the bottle, but return again after the lower half of the bottle is in the recess, 45 and close in on each side about portions of the upper half thereof. The bottle is thus yieldingly held in the pocket in gripping relation and is prevented from wobbling or other minor movements.

50 Due to the alternate neck and body arrangement of the tray and its ability to readily lend itself to adjustment, it is obvious that two neck portions on each side of a body portion may be further reduced by the insertion of a bottle, so that when part or all of the tray is filled, the bottles are nicely gripped and cushioned as seen in Fig. 3.

Experience as well as repeated experiments disclose that breakage is due not so much to 60 contact by the bottle with external agencies as to mutual contact as between the bottles themselves. Likewise, in the majority of instances, the bottles are broken at the shoulders or necks which are usually the weaker portions thereof. 65 Accordingly, the present improvements are developed to minimize breakage, especially at such areas. In the contraction of the tray, the shoulder portions of the recesses are free to approach the bottles and serve to grip and doubly cushion 70 the shoulders thereof. Furthermore, since the recesses are longer than the bottles, the latter are staggered slightly which disposition contributes to the cushioning and protecting features at the shoulder portions.

75 It is notable that when bottles are reclined,

the liquid contents seek their own level so that the air space is commonly disposed at A (Fig. 1). Where the contents are carbonated, as, for example, in ginger ale, occasional shaking of the bottle liberates the gas into air space A, creating a pressure adjacent the bottle shoulder. The strain on the bottle at these points is minimized and the liability of breakage decreased by the aforementioned shoulder protection as well as by the gripping action of the pocket and the closed ends 19, 20, thereof, all of which contribute to cushion shocks and prevent shaking or jars which may set up pressure in area A. It is well known that such internal pressure, set up by shaking the bottle, may force out or loosen the cork or cap, with attendant loss of the contents. Such a possibility is eliminated also, during shipment, by the described functions of the improvements.

80 Due to the adjustability of the individual pockets and the tray filler as a whole, one size of filler may serve for a plurality of different sized outer cartons. Furthermore, one size filler is sufficient, within prescribed limits, to accommodate bottles of varying size. It is notable also that the smaller the bottle, the smaller the carton and pockets of the filler when the tray is compressed into the carton.

85 For purposes of display, the improved tray may act as a support to sustain the bottles inclined to the horizontal. Without removing the bottles from the tray or carton, their necks may be canted upwardly, so that the pocket walls approach one another beneath the shoulder and form a support therefor.

90 Referring to Figs. 7 and 8, the bottom neck 110 portions of the recesses may be provided with a protuberance 26 of any desired shape or form, so as to function as a leg for such portion and prevent it from being depressed below its prescribed level.

95 In Figs. 9 and 10, complete bottle cartons are illustrated. In Fig. 9, the body portion 33 has pockets more than half bottle size while the cover 34 has complementary pockets of less than half bottle size. The embodiment in Fig. 10, 100 illustrates the body portion 35 with full bottle size pockets, with a flat cover 36. These cartons may be suitably labeled or stamped to indicate the contents.

105 Provision is preferably made for the carriage 115 of three bottles, which makes a neat and handy parcel. However, the number of pockets may be increased or decreased in these, as well as in any of the embodiments, without departing from the scope of the improvements.

110 It is understood that the improvements may be designed and adapted for packing other merchandise, and are therefore not limited to the embodiments selected for illustration and description.

115 I claim:

120 1. A device of the character described comprising a tray formed of resilient material, said tray having a plurality of bottle shaped recesses 125 adapted to receive bottles in reclined position, said recesses being deeper than the half section of a bottle and having mouths wider than the diameter of the bottles to be packed.

130 2. A self-adjustable tray formed of relatively 135 yieldable material, said tray having a plurality of preformed elongated article conforming recesses, said recesses having mouth-defining walls extending above the horizontal medial line of the articles to be received therein, whereby com-

200

pression of said tray in a direction across said recesses will bring said walls closer together.

3. The combination with a packing carton, of a normally oversize non-foldable filler therefor comprising a tray of relatively yieldable material having one dimension normally greater than the corresponding dimension of the carton, said tray having elongated article conforming recesses disposed substantially at right angles to the said greater dimension each recess extending over half the width of the lesser dimension, said tray being compressible in the direction of said greater dimension for disposal in said carton whereby the areas defined by said recesses are altered.

15 4. The combination with a packing carton, of a normally oversize filler therefor comprising a tray of relatively yieldable material, said tray consisting of bottle-shaped depressions substantially traversing the tray, said depressions being deeper than a half bottle section, said tray being oversize only laterally of said depressions, whereby insertion of said tray in the carton will

contract the tray and depressions thereof for holding bottles in gripping relation.

5. In a resilient packing tray for fragile articles, an individual article compartment comprising an elongated recess adapted to have an article inserted laterally therein, said recess having a depth slightly greater than half the diameter of the article and a mouth wider than the diameter of the article, the arrangement being such that the sides of the recess defining the mouth are adapted to be moved inwardly about a portion of the upper half of the article.

10 6. A performed tray of relatively yielding moulded pulp material having a plurality of elongated recesses adapted to receive fragile articles in a reclining position, the depth of said recesses, when the tray is positioned within a carton, being sufficient to snugly accommodate the lower half of packed articles, portions of the peripheral edges of such recesses exerting a gripping action on said articles for yieldingly retaining them within the recesses.
